COSMETIC KIT

Annette Grosso, East Orange, N. J.

Application June 2, 1955, Serial No. 36,341

Term of patent 14 years

(Cl. D86—10)

Fig. 1.

Fig. 2.

Fig. 4.

Fig. 3.

Fig. 1 is a top plan view of a cosmetic kit embodying my new design.

Fig. 2 is a side elevation of the cosmetic kit shown in Fig. 1.

Fig. 3 is a top plan view of the cosmetic kit with the lid removed.

Fig. 4 is a side elevation of that portion of the cosmetic kit shown in Fig. 3.

I claim:

The ornamental design for a cosmetic kit, as shown.
